(57) **CLAIM**

The ornamental design for an electrical connector, as shown and described.

DESCRIPTION

FIG. 1 is a front, top and right perspective view of an electrical connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines depict portions of the electrical connector in which the design is embodied that form no part of the claimed design.

The dot-dash lines represent the boundaries of the claimed design that form no part of the claimed design.

The shade lines on the surface of the electrical connector indicate contour and not surface decoration.
